UNITED STATES PATENT OFFICE.

FRED H. CHARLESWORTH, OF ST. PAUL, MINNESOTA.

CASKET.

Application filed March 16, 1922. Serial No. 544,294.

To all whom it may concern:

Be it known that I, FRED H. CHARLESWORTH, a citizen of the United States, residing at St. Paul, in the county of Ramsey 5 and State of Minnesota, have invented new and useful Improvements in Caskets, of which the following is a specification.

My invention relates to burial caskets and particularly to the type of casket having inwardly inclined closure members hinged to the sides of the same which act in conjunction with the top of the coffin to effect the complete closure therefor and has for its object to provide a device for simultaneously 15 opening and closing all of said inclined closure members.

Another object of the invention is to rigidly attach the cover of the casket to the rear closure member so that the same may 20 be moved in unison.

A still further object is to construct and arrange the parts of my invention so that when the rear member is positioned with the cover in substantially vertical position 25 that the two remaining members will lie substantially horizontal.

In carrying out my objects I preferably hinge the said closure members to the side of the casket mitering the same at the corners 30 thereof. To each of the side members is connected a link which is pivoted to a swinging arm pivoted to the body of the casket, and to the end member is pivoted a hinged link which is likewise pivoted to said arm, 35 which parts are so constructed that when one of said members is swung upon its hinge the others are caused to simultaneously swing with it and to open or close as required.

The full objects and advantages of my invention will appear in connection with the detailed description thereof and are particularly pointed out in the claims.

In the drawings, illustrating the application of my invention in one form:—

Fig. 1 is a plan view of a shell of a casket showing my invention applied thereto with the hinge members and top in open position.

Fig. 2 is a sectional view taken on line 2—2 of Figure 1.

Fig. 3 is a sectional view taken on line 3—3 of Figure 1.

Fig. 4 is a view similar to Figure 3 showing the arrangement of the parts when the casket is completely closed.

In the conduction of funerals it is a well-

known fact that the ease and grace with which the director can manipulate the various members of the casket to effect closure of the same after the services have been completed are essentials which play an important factor in the pleasing and serving of the director's clients, and that the director's reputation is involved in the successful performance of this portion of the services. My invention permits the director to effect a complete closure of the casket with one hand giving him the free use of the other hand to rearrange and tuck in the upholsteries and to gracefully and quickly effect the closure 70 of the same.

Although my invention can be applied to caskets of any description such as the state, elliptical, octagon or other forms, I have simply shown it in this application as applied to a casket shell of the octagon type which is indicated in its entirety at A. This shell may be of ordinary construction consisting of a bottom 10, two side members 11 and 12, and ends 13, which ends and side members are connected by diagonally positioned sides 14 best shown in Figures 1 and 2. To the upper edges of the the sides and ends 11, 12, and 13 are hinged- 80 and 21 which are perimetrically arranged along the entire casket and slope inwardly towards one another as best shown in Figure 4. These members which are often referred to in the trade as "OG's" have angular portions 22 rigidly secured to the ends of the same which extend half-way along the edges of the side members 14 so that when the structure is closed a continuous structure is formed along the entire casket 95 which slopes inwardly and is elevated above the upper edge of the sides of the same.

It will be noted that the members 16 and 18 lie continuous with the members 19 and 21 and that the points of connection of the same fall opposite each other. In placing the body within the casket all of the said members are swung back. When the body is in position members 19, 20 and 21 are closed as shown in Figure 1 with the members 16, 17, and 18 open so as to display the bust of the body as positioned within the casket.

The top of the casket consists of two sections 23 and 24 of which the section 24 may be fastened to the members 19, 20, and 21 by latching devices such as are now in common use in the art and which are not shown in the

drawings. The cover section 23, however, is rigidly secured to the member 16 as can clearly be seen in Figure 3 so that when the said member is tilted backward the cover is supported thereon in an elevated position as indicated.

My invention consists principally of a device for simultaneously manipulating all of the sections 16, 17 and 18 at one time by opening and closing of the cover section 23. This device comprises a plate 25 which is screwed to the side 13 of the coffin and which has a trunnion 26 issuing outwardly therefrom. Rotatably mounted upon said trunnion is a lever 27 having two arms 28 and 29 connected together and pivoted to said trunnion at their point of juncture. A nut 30 screwable upon the end of the said trunnion 26 serves to hold this lever properly positioned for oscillation.

At the extreme end of arm 27 is pivotally mounted a connecting link 31 which is formed with an angular bend 32 near the said end. This link is pivoted at its other end to a bearing 33 which is secured to the angular portion 22 formed on member 16. In a similar manner another link 34 having an angular portion 35 is pivoted to the extreme end of arm 29 at one end and to a bearing 36 secured to angular portion 22 of member 18. Arm 29 is formed with a bent up portion at 38 at which location is pivotally connected thereto a link 39 which extends upwardly to a height about level with the top of member 17 when the same is in its open position. The extreme end of this link is hingedly connected at 39 to another link 40 which in turn is pivoted to a bearing 41 secured to member 17.

The parts of the invention are so proportional and designed that when the cover section 23 is in vertical or upright position and the members 17 and 18 positioned in substantially horizontal location that the various parts take their relative positions as indicated in Figure 3. It will here be noted that the points of pivot of bearings 36 and of link 34 to the arm 29 and the trunnion 26 are practically in alignment so that further movement of the member 18 is prevented. The same is not true of cover section 23 and member 16. In the latter case the said bearings are sufficiently out of alignment so that the device exerts sufficient pressure upon lever 27 to hold the parts free from movement, and so that the device may be operated by movement of said cover. When link 37 hits against the end member 13 of the casket movement of member 17 is also retarded so that when the link mechanism is positioned as shown in Figure 3 all of the parts are firmly held in proper position without danger of disengagement or passage beyond the position other than that required.

In closing the device it is merely necessary to grasp the cover section 23 and to swing the same downwardly. This has the effect of oscillating lever 27 which in turn oscillates the links 34 and 37 thereby swinging the members 17 and 18 upwardly and towards one another. As the links began to swing the same rest upon the upper ends of the sides of the casket which serves as a fulcrum for the pivotal movement of the same. This has the effect of swinging the members 17, 16, and 18 upwardly until the same are somewhat raised above their horizontal position. After this the said links pull directly on the said members tending to further close them. In this manner by manipulating the cover section 23 all of the members 16, 17, and 18 are simultaneously moved by the operating mechanism of my invention. When the parts are completely closed the same take the relative positions as shown in Figure 4. On reversal of the operation the cover section 23 may be similarly opened from its position shown in Figure 4 and members 17 and 18 simultaneously opened therewith until the parts take the position shown in Figure 3 where the alinement of the points of pivot of link 34 and lever 29 cause the movement of the same to terminate.

In completed coffins or caskets the entire shell including the members 16, 17, and 18 is completely upholstered with materials and by methods now in common use in the art. This construction is shown in the drawings in dotted lines at 55 and with the same all of the links and levers used in connection with the device are completely covered so that when the coffin is in actual use none of the operating parts necessary to the manipulation of the device as required can be seen.

As the director of the funeral terminates the services and closes the casket the same may be done by him with one hand by grasping the cover section 23 and slowly and carefully swinging the same downwardly. This leaves him with his other hand free to fold over and tuck in the upholstery as the various members 16, 17, and 18 come together so that said members may properly close and so that none of the white upholstery or interior of the casket may be visible to the exterior after the same has been completely closed.

The advantages of my invention are manifest. A very inexpensive device can be provided which performs the desired results and which will not easily get out of order. The entire structure can be concealed beneath the upholstery so that no operating parts would be visible. In addition the movement of the parts is such that squeaking or noise is entirely eliminated.

In accordance with the patent statutes I

have described the principles of operation of my invention, together with the apparatus which I now consider to represent the best embodiment thereof, but I desire to have
 5 it understood that the construction shown is only illustrative and that the invention can be carried out by other means and applied to uses other than those above set forth within the scope of the following
 10 claims.

I claim:—

1. A closure for a casket including a plurality of cover members, means adapted to be concealed beneath the upholstery of the
 15 casket, said means comprising a member pivotally connected to the wall of the casket and a series of arms connected to said member on one end and the outer ends being connected to said cover members whereby said
 20 casket is closed by the movement of one of said cover members.
2. A casket including a series of cover members hingedly connected thereto, an upholstery covering for the inner surface of
 25 said casket and cover members, means concealed beneath said upholstery and adapted to connect said cover members in a manner to move said members simultaneously into open or closed position.
3. A casket comprising a series of cover members hingedly connected to the body of
 30 said casket, a lining for said casket and cover members, means concealed beneath said lining adapted to connect said cover
 35 members in a manner to cause the same to move in unison into open or closed position without disclosing said connecting means.
4. A casket including a series of closure members pivotally connected to the body of
 40 said casket, a lining adapted to cover the inner surface of said casket and to continue over the inner surface of said closure members, means adapted to be concealed beneath said lining for operating said closure
 45 members in unison, said operating means comprising a quadrant and arms connecting said closure members with said operating quadrant.
5. A casket including a series of closure
 50 members hingedly connected to said casket, each closure member moving in a different direction, means adapted to operate said closure members in unison, said means including a member pivotally connected to the
 55 wall of the casket and a series of arms connecting said closure members with said pivot
 60 ed member in a manner to permit said closure members to move in unison and in unequal distances when in open position.
6. A casket closing device comprising an
 65 operating quadrant adapted to move in a single plane, a member connected to said operating quadrant adapted to move with it in substantially the same plane and a second member connected to said operating quad-

rant in a manner to cause a portion thereof to move simultaneously with and in a plane substantially at right angles to the plane of movement of said quadrant.

7. A casket closing device comprising an
 70 operating head adapted to move in a plane, a closing member connected to said operating head and adapted to move with it in the plane of movement thereof and a second closing member connected to said operating head and adapted to move simultaneously with and in substantially a plane at right angles to the plane of movement of said operating head.

8. A casket closing device including a series of cover members, means positioned within the casket and comprising pivotally connected members adapted to permit said cover members to be opened simultaneously and operatively associated with the cover
 85 members so as to hold them in different positions with one cover member extended into a position more remote than the other cover member from the body of said casket when in open position.

9. A casket comprising a series of closure members hingedly connected to the body of the casket in a manner to cause them to be positioned at an inwardly inclined angle when closed, a horizontally extending cover member secured to one of said closure members and adapted to move with the same, means for operating said closure members in unison including a quadrant pivotally connected to the wall of said casket, and
 90 members connecting said quadrant with said inclined closure members to operate them in unison and to cause said closure members to move into different positions so that the members are unequally moved about their
 95 hinging point on said casket.

10. A casket including a series of closure members hingedly connected thereto to position the same at an inwardly inclined angle from the body of the casket in closed position, a cover member fixed to one of said closure members and means pivotally connected within said casket adapted to move some of said closure members to extend at an obtuse angle from their closed position while the
 115 member carrying said cover is adapted to move simultaneously into position at approximately right angles from its closed position with the cover member extending in substantially a vertical plane when the closure members are in open position.

11. A casket closing device including means pivotally connected within said casket, a series of arms pivotally connected to said means, said arms being adapted to move the cover portions of the casket in different directions simultaneously to open said casket and to vary the rate of movement of said cover members in relation to each other.

12. A casket closing device adapted to control the movement of three closure members including a series of operating levers adapted to move the three closure members simultaneously in a manner to vary the extent of movement of the closure members when in open position. 35
13. A casket comprising a plurality of closure members adapted to form a top cover therefor and means adapted to connect said closure members in a manner to move said closure members into different positions in relation to each other when open and to bring them in unison to the same relative position with each other when the cover is closed. 40
14. A casket comprising a cover formed with a plurality of cover members adapted to be positioned at an inwardly inclined angle when closed, a cover member secured to one of said members extending across and forming the top cover portion of said casket, a quadrant positioned within said casket, a series of arms connecting said quadrant with said cover members whereby all of said cover members are moved in unison into open position with some of said cover members extending beyond the point of opening in relation to the other of said members, all of said members being adapted to close into the same relative position by the operation of said quadrant and connecting members. 45
15. A casket closure including a plurality of closure members, a series of lever mem- bers connected to said closure members and an operating member adapted to move said levers to advance one closure member ahead of the other, to arranged said closure members at different positions when open and in a symmetrical position when closed. 50
16. In combination with a casket having a body, closure members hinged to the walls thereof and adapted to move towards one another to effect the closure of the same, an arm pivoted to said body and links pivoted to said closure members and to said arm for causing all of said closure members to simultaneously move upon oscillation of said arm, one of said links including a hinged joint. 55
17. In combination with a casket having a body formed with sides, inclined closure members hingedly connected to the sides of said body and adapted to move towards one another, a cover firmly secured to one of said closure members whereby the same moves in unison therewith, and means for interconnecting said inclined members so that all of the same move simultaneously upon movement of said cover member. 60
18. A casket having a cover comprising a series of members, means connecting said members in a manner to cause them to move into open or closed position simultaneously, and concealing means for covering said connecting means for the members of said cover. 65

In witness whereof I affix my signature.
FRED H. CHARLESWORTH.
